UNITED STATES PATENT OFFICE

2,254,003

COMBINED WASHING AND RINSING
MACHINE

Louis De Marco, Cleveland, Ohio

Application February 10, 1940, Serial No. 318,317

3 Claims. (Cl. 68—196)

This invention relates to combined clothes washing and rinsing machines and has for its general object to provide means whereby a washing machine structure may be utilized in an economical and efficient manner for enabling the clothes to be rinsed therein and removed therefrom after the conclusion of the washing operation. In my Patent No. 2,161,022, issued June 6, 1939, there are shown, described and claimed a means for enabling a washing machine of one type of standard construction to be utilized as a rinsing machine and wherein this result is accomplished by suspending a perforated cover within the top of the tub of a washing machine, wherein the cover is provided with a central opening to permit the top of the rotor to extend therethrough, and the body of the tub is provided with an overflow located above the said cover element.

My invention herein has for one of its more limited objects to provide the tub of a washing machine with rinsing means including a cover element having a perforated bottom portion and which cover element is removably applied to the top of the tub and wherein the perforated portion of the bottom is provided with means for effectively handling and disposing of the soapy water contained in the clothing after the preceding washing operation.

A further object of my invention is to provide a cover element of this type with means whereby substantially all of the liquid which may be passed through the perforations of the bottom portion of the same may be quickly and conveniently removed at the conclusion of the rinsing operation.

I accomplish the foregoing objects in and through the construction and arrangement of parts shown in the appended drawing, wherein Fig. 1 represents a central vertical section through the upper portion of a washing machine embodying my invention, the rotor being shown in elevation; and Fig. 2 a detail in section taken on the line 2—2 of Fig. 1.

Describing the construction and arrangement of parts shown in the said drawing, 1 denotes the tub of a washing machine of standard construction, the same having a bottom 2 on a supporting base 3, and provided at its top with an open outwardly concave bead 4 extending therearound.

5 denotes the body of an agitator of the rotor type having the usual blades 6, the rotor being driven through the said body by means of a shaft therewithin in the usual manner, as shown, for

instance, in my aforesaid patent. As the means for driving the rotor are old and well known, and as such means in their details form no part of my invention herein, illustration and description of the same are unnecessary.

7 denotes a drain connection in the bottom of the tub, the same being provided with a valve 8.

The construction and arrangement of all of the foregoing parts are those employed in a well known type of washing machine and need no further description.

In order to convert the machine thus shown and described into an effective rinsing machine, I have provided the following construction: 9 15 denotes a cover element, the same having a top wall 10, a perforated bottom wall 11, and a side wall 12. Extending from said cover element above the bottom thereof is a wide outwardly and downwardly extending discharge spout 13, the same having its delivery outlet 14 located below the top of the tub and below the perforated bottom 11. Adjacent to its lower end, the cover element is provided with a flange 15 providing with the portion of the side therebelow a downwardly extending channel having a gasket 16 seated therein. The inner wall of the channeled seat is extended downwardly below the bottom 11 to provide an annular rim 17 which fits within the bead 4.

30 The cover element may be secured in place by means of a hook 18 located beneath the central lower portion of the spout and by one or more hooks adapted to be swung into engagement with the outer downwardly and outwardly extending edge of the bead 4, each of said hooks being adapted to be operated by a lever shown as comprising side members 19 and a handle 20. The lower ends of the side members are mounted upon a shaft 21 extending through lugs 22 projecting upwardly from the channel flange 15 and the upper ends of the said side members are connected by a pin 23 mounted therein with the upper end of the hook 24 the lower end of which is adapted to be swung beneath and engage the outturned end of the bead 4 when the lever is moved to the position shown in Fig. 1. As stated, more than one of these locking members 15—24 may be provided for the cover element, if desired. In addition, the cover element is provided with handles 25 to permit its application to or removal from the top of the tub. The bottom 11 of the cover element is a plate provided with upwardly tapered openings 26 and with radial ribs 27 and concentric circular ribs 28, the rim 17 constituting the outermost of the said concentric ribs.

Adjacent to the spout 13, the bottom is depressed to form a sump 29, preferably oval in outline, with its longer axis transverse of the axis of the spout. The said sump is provided with upwardly tapering openings 30 in the extreme bottom thereof and with upwardly and inwardly tapering openings 31 extending entirely about and through the wall of the sump intermediate the bottom and the top thereof. Between the series of openings 30 and 31, the downwardly and outwardly extending ribs 32 are located.

The bottom of the sump thus described cooperates with the remainder of the bottom of the cover element in providing for the delivery of rinsing water therethrough, while the ribs on the sump as well as those on the remainder of the cover element prevent the articles being rinsed from being forced into engagement with the portion of the bottom intermediate said ribs and from clogging the openings therethrough. In addition, and at the conclusion of the rinsing operation, the sump provides part of the means for effecting speedy removal of any water which may tend to remain below the bottom of the receiving end of the spout, both above the bottom of the cover element and within the top of the tub to the level of the bottom of the tube within the sump. Cooperating with the sump is a siphon tube 33 having its inner end in close proximity to the depressed central portion of the sump and extending through and below the spout 13 and having its lower end located a distance below the said sump and provided with a valve 34. The provision of the two series of openings 30 and 31 in the sump is for the purpose of securing an ample supply of liquid to the sump at all times until the lower end of the siphon tube is unsealed.

With the parts constructed and arranged as described, the operation will be readily understood. The water for washing the clothes or other articles may be placed in the tub in the usual manner, or supplied through the drain connection 7 by slipping over the end thereof a hose 35 having at its opposite end a faucet 36. After the tub has been filled, for washing purposes and soap added thereto, the rotor 5 will be operated to agitate the articles in the soapy water in the tub. The clothing may then be removed and one or more new batches added and washed with the same water.

At the end of the washing operation, the soapy water will be withdrawn through the drain connection. The clothing which has been washed will be wrung to remove excess dirt and soapy water therefrom, after which the batches will be put into the tub and each batch treated as follows: The cover element 9 will be applied to the top of the tub by first engaging the hook 18 beneath the bead 4, as shown, and thereafter moving the cover downwardly to its seat upon the top of the said bead and by locking the operating lever (or levers) 19, 20 in the manner described to lock the other portion of the cover element in place. Water for rinsing purposes may then

be supplied to the tub while the rotor is operating. This will enable the water to pass in contact with and through the batch of clothing to be rinsed as the latter are being agitated by the rotor and the soap or any sediment which may still remain in these articles will be completely removed therefrom, the water containing the soap and sediment being delivered through the waste pipe 13. The shape of the openings 26, 30 and 31 enables the soap to be collected about the edges thereof and the combination of the radial and circular ribs provides traps for the soapy water which prevents the latter from sloshing around and retarding the rapid delivery of the soapy water from the articles and from the tub.

At the conclusion of the rinsing operation, the valve 36 will be closed and the valve 34 opened, and any water that may be within the machine above the perforated bottom and also below the said bottom to the level of the bottom of the inner end of the siphon tube will be withdrawn through the latter. This will enable the operator to disengage the cover element from the tub and remove the cover without liability of spilling water upon herself; also, because the water will have been withdrawn below the top of the tub by the action of the siphon tube, the operator will be enabled to remove the clothing from the tub without liability of spilling water over the top of the latter and upon herself. The ribs 32 which substantially surround the openings 30 and 31 prevent these openings from being clogged by the articles of clothing in the upper portion of the tub.

Having thus described my invention, what I claim is:

1. A removable cover element for the tub of a machine of the character described, the said cover element having a side wall and a perforated bottom wall below the top of said side wall, the said cover being provided with a discharge outlet communicating with the space above said bottom wall, the said bottom wall having a sump extending therebelow and adapted to communicate with the space thereabove and provided with one or more openings communicating with the space therebelow, and a siphon tube having an upper receiving end located within said sump below the portion of the bottom wall thereabove and extending through the side wall of the cover and having its lower delivery end located below its inner receiving end and provided with a valve.

2. The cover element recited in claim 1, wherein the said openings in the sump are provided with downwardly extending ribs adjacent to the said openings.

3. The cover element recited in claim 1, wherein the said discharge outlet is an outwardly and downwardly extending discharge spout, and wherein the said siphon tube extends through the said spout and has its delivery end located therebelow.

LOUIS DE MARCO.
